UNITED STATES PATENT OFFICE.

SAMUEL HARRY NORTON, OF MEADVILLE, PENNSYLVANIA, ASSIGNOR TO THE
McCROSKEY REAMER CO., OF MEADVILLE, PENNSYLVANIA, A CORPORATION
OF PENNSYLVANIA.

ADJUSTABLE REAMER.

1,250,630.

Specification of Letters Patent. Patented Dec. 18, 1917.

Application filed April 17, 1917. Serial No. 162,593.

To all whom it may concern:

Be it known that I, SAMUEL H. NORTON, a citizen of the United States, and a resident of Meadville, in the county of Crawford and State of Pennsylvania, have invented a certain new and useful Improvement in Adjustable Reamers, of which the following is a specification.

My present invention relates generally to 10 reamers, and more particularly to an adjustable reamer, my object generally being the provision of an improved device of this nature involving a construction whereby the cutters may be effectively secured and 15 clamped adjacent their forward outer ends, and a compact arrangement involving a minimum number of parts is at the same time promoted.

A further object of my invention is to 20 provide a construction including a combination of special parts whereby an effective small reamer may be placed upon the market at minimum cost and without danger of 25 "chattering" in use.

These and other objects residing for the most part in the details of construction, arrangement, and operation in which my invention in its specific aspect lies, will be 30 better understood from the following description in which reference is made to the accompanying drawings forming a part of this specification, wherein:

Figure 1 is a side elevation of my improved adjustable reamer;

Fig. 2 is a vertical longitudinal section through the forward end of the effective operating parts thereof;

Fig. 3 is a front elevation, and

Fig. 4 is a cross section taken substantially 40 on line 4—4 of Fig. 2.

Referring now particularly to these figures, my improved reamer includes a handle portion 10 cylindrical in form, which in the present instance, as particularly shown in 45 Fig. 2, is provided at its forward end with an enlarged axial bore 11 receiving the rear cylindrical extension 12 of the reamer shank 13, onto which extension 12 the forward portion of the handle is shrunk. It is to be 50 understood that my invention is not limited to such a construction, as it is possible to form the handle 10 integrally with the shank 13 in sizes where the shank is of greater diameter than that of the handle.

55 At its forward end the shank 13 has an

enlarged cylindrical head 14, and is externally threaded at 15 between its extension 12 and the said head, for the reception of an adjusting ring 16 which is internally threaded, as seen in Fig. 2, to coöperate with the threads 15 of the shank, and which is movable upon the threaded portion of the shank for the full length thereof.

The threaded portion 15 of the shank 13 and the head 14 thereof are provided with 65 longitudinally extending grooves 17 at spaced points therearound, the bases of which grooves taper from the relatively shallow forward ends at the forward ends of the head 14 to the relatively deep ends adjacent the rear end of the threaded portion 15 of the shank. These grooves receive elongated cutters 18, the inner edges of which are tapered in conformity to the taper of the groove 17 and the forward cutting edges 19 of which 70 project beyond the forward end of the head 14, the rear beveled ends 20 of these cutters being engaged by the conical forward end of the adjusting ring 16, so that the latter when rotated snugly against the rear ends 75 of the several cutters, serves to hold the latter in the grooves 17.

The head 14 is, furthermore, slotted throughout its length, the slots indicated at 80 21 extending inwardly therethrough from the bases of the grooves 17 to the axial bore 22 of said head, so as to thus form relatively adjustable segments 23, as particularly seen by a comparison of Figs. 2 and 3, adjustment of which toward one another serve to 85 firmly and effectively clamp the forward effective ends of the cutters 18.

To this end the head 14 has diametrical openings through its segments at right angles to one another, and at points spaced 90 longitudinally of the head adjacent its forward end, for the reception of clamping screws 24, the openings of certain of the segments being threaded to receive the threaded portions of the screws, as seen in 100 Fig. 3, with the opposite openings counterbored so as to countersink the heads of the screws.

Thus, in adjusting the cutters 18 it is simply necessary to loosen the clamping 105 screws 24 and turn the adjusting ring 16 more or less, as desired, to force the cutters forwardly by virtue of such movement of the adjusting ring, and outwardly at the same time by virtue of the coacting tapered 110

edges of the cutters and bases of the grooves 17. The clamping screws 24 are then tightened to effectively clamp the cutters adjacent their forward ends.

5 It is further to be noted from Fig. 1 that the grooves of the cutters, and consequently the cutters themselves, extend in slightly angular positions relatively to the longitudinal axis of the reamer, with their forward effective ends inclined away from the direction of rotation of the reamer in use, so as to thus defeat any tendency of the reamer to feed itself forwardly in use and, 10 with the effective clamping of the forward ends thereof, eliminate all danger of "chattering."

It is obvious that from the construction described, I am enabled to provide an effective reamer of small diameter in which 20 a minimum number of parts are employed and a minimum number of cutters necessitated, although it will be understood that my invention is not to be limited to the use of four cutters, as shown in the drawings.

25 I claim:

1. An adjustable reamer including a threaded shank, having a head at its outer end, and provided with lengthwise grooves therealong and along the head having tapering bases, an adjusting ring threaded upon the shank, cutters disposed in the said grooves and having tapering inner edges co-operating with the tapered bases of the 30 grooves, said head having an axial bore, and 35 slots extending from the said grooves and

the said bore for substantially the length of the head to form segments between the outer ends of the cutters, and clamping screws extending diametrically through the head whereby to connect the said segments and 40 securely clamp the outer portions of the cutters thereby.

2. An adjustable reamer including a threaded shank having a head at its forward end, the latter of which has a series of integral segments, said shank and its head having tapering cutter receiving grooves, cutters disposed in the said grooves, an adjusting ring threaded upon the shank to engage the rear ends of the cutters, and clamping screws extending diametrically through the head at longitudinally spaced points 45 near the forward end thereof, whereby to connect the segments of the head and securely clamp the forward portions of the 50 cutters thereby.

3. An adjustable reamer including a threaded shank having an enlarged longitudinal split and longitudinally bored head at its forward end, said shank and its head 60 having external longitudinal cutter receiving grooves, cutters disposed in the grooves, an adjusting ring threaded on the shank and engaging the rear ends of the cutters, and clamping means extending diametrically 65 through the head and connecting the split portions thereof for clamping the forward ends of the said cutters.

SAMUEL HARRY NORTON.
